UNITED STATES PATENT OFFICE

PAUL I. A. RUNGE, OF SAN FRANCISCO, CALIFORNIA, ASSIGNOR TO WILLIAM H. GALVIN,
OF SAN FRANCISCO, CALIFORNIA

AUTOMOBILE HEADLIGHT

Application filed January 23, 1929. Serial No. 334,425.

This invention relates to an automobile headlight and more particularly to an automobile headlight having an adjustable reflector.

5 The principal object of this invention is to eliminate glare from the headlight.

Another object is to provide means for changing the position of the reflector within the headlight at the will of the driver.

10 A further object is to provide means for tilting the headlight to raise or lower the beam of light.

A still further object is to provide simple means for the replacement of a light bulb 15 in the headlight.

Other objects of the invention will be apparent as the description proceeds.

In the following description and the accompanying drawings the invention is disclosed in two preferred embodiments, but it is to be understood that the invention is not confined to these forms because it may be embodied in other forms. It is also to be understood that in and by the claims following the description the invention is desired to be covered in whatsoever form it may be embodied.

Fig. 1 is a vertical sectional view of the headlight.

30 Fig. 2 is a front elevation of the same.

Fig. 3 is a detail view of the headlight showing one of the slides which carries the reflector.

Fig. 4 is a side elevation of the modified 35 form of the auxiliary headlight.

Fig. 5 is a vertical sectional view of the headlight shown in Fig. 4.

Fig. 6 is a back view of the reflector showing the means for connecting it to the slide 40 and operating mechanism, and

Fig. 7 is a plan view of the clamp used for securing the lamp on the filling neck of a radiator.

The socket 3 is fixed to the conventional 45 standard 1 which supports the yoke 2. The cylindrical drum portion 4 of the headlight has the conical back end 3' and is provided with a conventional glass pane 4', which is retained in position by means of the flanged 50 ring 5.

Within the cylinder 4 are two fixed slides 6 and 7 which carry the reflector 8. The reflector is of the concave spheroidal type, with a suitable metal backing 9, which has extensions 10 and 11 to operate in the slides 55 6 and 7. The metal backing 9 is connected to a yoke 12, which is threaded on a rod 13, which is held in a fixed lateral position by the bushing 14 at the back of the casing 3'.

The rod 13 is flexibly connected to the rod 16 by means of the universal joint 15. The rod 16 extends through the dash and is bent to form the crank 17. Turning the crank 17 rotates the threaded rod 13 and 60 thereby slides the reflector 8.

The bracket 18 is pivotally mounted behind the pane 4' and carries the electric light socket 19 with the electric light globe 20 therein. A rubber pad 21 is placed on the back of the socket 19 and contacts and plane 4' to hold the bracket 18 in position and to prevent its rattling.

The insulated wires 22 and 23 extend through an insulated bushing 24 and are connected to the socket 19 in the conventional manner. These wires 22 and 23 carry current from the automobile battery to the light globe 20 when the controlling switch is closed.

The focus of the light rays may be varied as may be required by adjusting the position of the reflector 8 with respect to the light bulb 20. When properly adjusted the headlight projects a strong light without the usual attendant glare.

When the pan 4' is removed the bracket 18 may be swung outwardly on its pivot to facilitate the replacement of the light globe 20.

In the form of the invention shown in Figs. 4 to 7 inclusive, means are provided for raising and lowering the rays of the headlight. This adjustment is controlled from the handle for varying the focus of 95 the rays.

The radiator 30 has the usual neck which is closed by the cap 31. The radiator neck is encircled by the clamps 32-33 on the end of the arm 35.

The bolt 34 holds the clamps rigid with the radiator neck.

The yoke 36 depends from the arm 35 and is pivoted thereto by means of the bolt 38.

5 This bolt may be loosened to permit angular adjustment of the yoke. The washer 39 holds the yoke in a fixed position when the nut 40 is tightened. The drum 37 is pivoted to the yoke 36 and is capable of rotary 10 movement at the will of the driver by means presently described.

The headlight comprises the cylindrical drum 37, having the angular flange 41 containing the glass pane 42. The back 43 of 15 the headlight is curved and is rigid with the cylindrical drum 37.

Within the drum 37 are two channels 44-45 which guide the ends of the arms 46-47, which extend from a central member 20 48. Also projecting from the member 48 are four angularly disposed arms 49-50-51 and 52 bent over the edges of the concave spherodial reflector 53.

The member 48 is connected to an arm 53 25 by the bolt 34. This arm extends to the top of the drum 37 and is provided with the hub 57 which engages the threaded rod 56, which is enclosed by the housing 58. The rod 56 is flexibly connected to the rod 62 by means 30 of two universal joints 59-60, which are joined by the rod 61. The rod 62 is supported by the bearing 64 which extends through the dashboard 66. The under side of the bearing is notched and engages the 35 plate 65 which is fixed to the dashboard 66.

Longitudinal movement of the rod 62 tilts the headlight on its horizontal axis to raise or lower the beam of light. The notches in the bearing 64 serve as stops to hold the 40 headlight in an adjusted position.

The end of the rod 62 is bent to form a crank 63. Rotation of this crank turns the rod 56 which slides the reflector, thereby adjusting the focus of the headlight. The 45 light globe 67 is carried in the socket 68 on the pivoted bracket 69, which is similar to that described in connection with the preferred embodiment of the invention. The rubber pad 70 bears against the pane 42 to 50 prevent rattling of the bracket.

The wires for the illumination of the lamp are shown at 71, 72 and extend through the back of the lamp and are protected by the dielectric bushing 73.

55 Having thus described my invention, what I desire to secure by Letters Patent of the United States is as follows, but modifications may be made in carrying out the invention as shown in the drawings, and in 60 the above particularly described form thereof, within the purview of the annexed claims.

1. An automobile headlight, comprising a 65 casing, a removable glass in the front of said casing, a bracket pivoted to said casing

and having an arm projecting to the center of said casing, a lamp socket on said arm projecting toward the back of the casing, a resilient pad on said arm adapted to bear against said glass, and a horizontal arm on 70 said bracket adapted to bear on the wall of the casing to limit the forward movement of the bracket.

2. An automobile headlight comprising a cylindrical casing, a removable glass front 75 for said casing, a light bulb mounted behind said glass front, a slidable reflector having guideways in said casing, an arm fixed to said reflector and extending through a slot in the top of said cylindrical casing, a 80 threaded rod engaging said arm, an operating rod extending from the dashboard of the automobile and flexibly connected to said threaded rod and adapted to rotate said threaded rod, thereby sliding said reflector in said casing, a pivot support for said cylindrical casing, thereby permitting tilting of said casing upon longitudinal movement of said operating rod.

90 In testimony whereof I have hereunto set my hand.

PAUL I. A. RUNGE.
